LOUDSPEAKER

Bo Arne Sjostedt, Trelleborg, and Stig Allan Valdemar Olsson, Vintrie, Sweden, assignors to Semiproduktion AB, Malmo, Sweden

Filed Feb. 22, 1971, Ser. No. 117,868

Term of patent 14 years

Int. Cl. D14—01

U.S. Cl. D26—14

FIG. 1

FIG. 2

FIG. 3

FIG. 1 is a perspective view of a loudspeaker embodying our new design;

FIG. 2 is an elevation view thereof; and

FIG. 3 is a top plan view thereof, the bottom plan view being substantially identical thereto.

We claim:

The ornamental design for a loudspeaker, substantially as shown and described.
